US00D533329S

(12) **United States Design Patent** (10) **Patent No.:** **US D533,329 S**
Baughman (45) **Date of Patent:** **** Dec. 5, 2006**

(54) **THREADED FLANGE FOR INSTALLATION
INTO A CONTAINER HEAD**

(75) Inventor: **Gary M. Baughman**, Auburn, IN (US)

(73) Assignee: **Rieke Corporation**, Auburn, IN (US)

(**) Term: **14 Years**

(21) Appl. No.: **29/215,656**

(22) Filed: **Oct. 22, 2004**

(51) **LOC (8) Cl.** **09-02**

(52) **U.S. Cl.** **D34/39**

(58) **Field of Classification Search** D34/39,
D34/11, 10; D9/434, 447, 4; 220/200, 234,
220/288, 256.1, 320; 285/203, 201, 202

(57) **CLAIM**

The ornamental design for a threaded flange for installation into a container head, as shown and described.

DESCRIPTION

FIG. 1 is a perspective view of a threaded flange for installation into a container head showing my new design;

FIG. 2 is a top plan view thereof;

FIG. 3 is a front elevational view thereof, the side elevational view being the same;

FIG. 4 is a bottom plan view thereof; and,

FIG. 5 is a front elevational view thereof, in full section, as viewed along line 5—5 in FIG. 2.
